US00D742944S

(12) **United States Design Patent**
Baro Cabrero

(10) **Patent No.:** **US D742,944 S**
(45) **Date of Patent:** **** Nov. 10, 2015**

(54) **HANDLE OF CUTTING WHEELS FOR CERAMIC CUTTING MACHINES**

(71) Applicant: **BELLOTA HERRAMIENTAS, S.A.,**
Legazpia (Guipuzcoa) (ES)

(72) Inventor: **Josep Baro Cabrero**, Legazpia (ES)

(73) Assignee: **Bellota Herramientas, S.A.**, Legazpia
(Guipuzcoa) (ES)

(**) Term: **14 Years**

(21) Appl. No.: **29/466,851**

(22) Filed: **Sep. 12, 2013**

(30) **Foreign Application Priority Data**

Mar. 15, 2013 (EM) 002203133-0004

(51) **LOC (10) Cl.** **15-09**

(52) **U.S. Cl.**

USPC **D15/127; D15/142**

(58) **Field of Classification Search**

USPC D15/127, 142

See application file for complete search history.

(57) **CLAIM**

The ornamental design for a handle of cutting wheels for ceramic cutting machines, as shown and described.

DESCRIPTION

FIG. 1 is an elevation view of a front side of the handle of cutting wheels for ceramic cutting machines showing my new design;

FIG. 2 is a side view of the design;

FIG. 3 is the elevation view of a rear side thereof;

FIG. 4 is the other side view of the design;

FIG. 5 is a plan view of the design;

FIG. 6 is a perspective view showing the front and side view thereof; and,

FIG. 7 is a perspective view showing the rear and side view thereof.

1 Claim, 7 Drawing Sheets
